UNITED STATES PATENT OFFICE.

WALTER FRENCH SLATER, OF MANSFIELD, ENGLAND, ASSIGNOR TO KIRKHAM, HULETT & CHANDLER LIMITED, OF LONDON, ENGLAND.

SPRAYER FOR EFFECTING INTIMATE CONTACT BETWEEN LIQUIDS AND GASES.

Application filed April 30, 1926, Serial No. 105,686, and in Great Britain June 2, 1925.

My invention relates to sprayers, such as are used in connection with centrifugal gas-washers and like apparatus for effecting intimate contact between liquid and gases.

According to the invention my improved sprayer comprises an inner boss or drum which is designed to be keyed upon a vertical shaft and is enclosed or surrounded by an outer wall or casing which is concentric with, and attached to it, so that it rotates therewith, the arrangement being such that an annular space is provided between the said central boss or drum and the outer casing. Above the outer casing, and either attached thereto or integral therewith, there extends a perforated rim or cylinder, and in the aforesaid annular space between the central boss or drum and the outer casing or cylinder I provide a number of lifting vanes or scoops which are suitably shaped or curved to constitute impellers for the purpose of lifting liquid from the bottom of the chamber in which the sprayer is mounted up into the interior of the sprayer. The liquid thus lifted is distributed on to the inner surface of the perforated cylinder or extension by means of one or more distributing guides located above the impellers, such guides being advantageously in the form of hollow inverted truncated cones, the outer peripheries of which may be in contact with, or be at a predetermined distance from, the inner surface of the said perforated rim.

In practice, the lifting scoops or impellers may be arranged so as to terminate at the bottom edges of the inverted cones; or they may be extended upwards beyond that point. Furthermore, the upper end of the perforated rim or extension may be furnished with an inwardly extending rim or flanges which may be either flat, curved or conical in shape.

To enable the invention to be fully understood I will describe it by reference to the accompanying drawings in which:—

Figure 1 is an elevation of a sprayer constructed in accordance with the invention for effecting intimate contact between liquids and gases.

Figures 2, 3 and 4 are, respectively, a sectional elevation, a central vertical section and a sectional plan view of the sprayer.

Figure 5 is a plan view of the shell of the sprayer and

Figures 6 and 7 are, respectively, an eleva-

tion and a plan view of the inner distributing conical guide.

Figures 8 and 9 are, respectively, an elevation and a plan view of the outer distributing conical guide.

Figures 10 and 11 are, respectively, a plan view and a side view of one of the lifting vanes or scoops.

Fig. 12 is a view showing the sprayer in connection with the enclosing casing or chamber.

a is the inner boss or drum of the sprayer located in each of the superposed chambers *p* and secured to the upright shaft *b* extending through said chambers. In the drawing the boss or drum *a* is shewn made in halves, each half having abutting lugs *c*, *c* so that they can be secured together and fixed tightly on the shaft *b* by bolts *d*, *d*. The said halves are also each shown with a projecting rib *e* designed to engage with a groove *f* in the shaft *b* to determine their position thereon. Other means than those shewn may, however, be employed for securing the boss or drum *a* to, and in proper position on, the shaft *b*.

g is the outer wall or casing of the sprayer concentric with, and attached to, the boss *a* by the screws or bolts *j* *h*, *h*, *i*, being the annular space provided between the said casing and boss. This casing *g* is shewn as being formed in halves secured together by bolts *g*.

j is the perforated rim or cylinder, which is shewn as being integral with the casing *g*, but it may be independent of, but attached to, the said casing.

k, *k* are the vanes, scoops or impellers arranged in the annular space *i*, which vanes are shaped or curved to lift the liquid from the bottom of the chamber, not shewn, in which the sprayer is mounted, up into the interior of the said sprayer when the latter is rotated by the shaft *b*. The impellers are shewn as being secured in position by the screws *h* passing through holes in lugs *k* on the said impellers.

l, *l* are the guides for distributing the liquid lifted by the impellers *k* on to the inner surface of the perforated cylinder *j*, the said guides being shewn in the form of hollow inverted truncated cones, the outer peripheries of which are shewn in contact with the inner surface of the perforated rim *j*, or they may be at a predetermined distance there-

from. The guides l , l' are advantageously made in halves having abutting flanges l^2 and are supported on the impellers k . In the drawing they are shewn located in slits m , m in the impellers so that the latter terminate above the bottom edges of the guides l , l' . The said impellers may, however, terminate at the bottom edges of the said guides.

n is the inwardly extending conical rim 10 with which the upper end of the perforated rim or cylinder j is provided and which is shown as being of conical form, although it may be flat or curved.

From the foregoing construction it will be 15 seen that when the shaft b is rotated in the direction of the arrow, Figure 2, the liquid, in which the lower end of the sprayer is immersed, will be raised by the impellers k to the inner surface of the perforated rim j below the upper edge of the smaller guide l and into both guides l and l' , up which the liquid 20 will travel and be distributed over the remainder of the inner surface of the perforated rim j the raised liquid being prevented 25 from passing out from the top of the said rim by the flanges n .

It is to be understood that the position 30 relatively to the impellers and conicity of the guides l , l' are such as to direct the liquid from the impellers k so as to provide a uniform or varying density of spray over the whole perforated surface of the rim or cylinder j .

Having now particularly described and 35 ascertained the nature of my said invention and in what manner the same is to be performed, I declare that what I claim is:—

1. A sprayer for effecting intimate contact 40 between liquids and gases comprising an inner drum designed to be attached to a vertical shaft, an outer wall concentric with and attached to the said drum and providing an annular space between them, a perforated spraying cylinder forming an upward extension 45 of the said outer wall, a series of vanes

arranged in the annular space between the drum and the outer wall and shaped so as to raise the liquid to be sprayed when the shaft is rotated, and means located above the vanes for directing the liquid raised thereby, over 50 the inner surface of the perforated spraying cylinder.

2. A sprayer as claimed in claim 1, wherein the means for directing the liquid raised by the impellers on to the inner surface of the 55 spraying cylinder are in the form of hollow inverted truncated cones.

3. In a centrifugal scrubber, a rotatable inner imperforate member, a rotatable outer imperforate member, a series of scoops positioned between said members adapted to be submerged at their lower ends in the liquid to be treated, a perforate member above said outer imperforate member, and inverted truncated cones arranged above said scoops to 60 carry the scooped liquid upwardly to said perforate member through which it is thrown by centrifugal action.

4. A rotative spraying element including a perforate cylinder, provided at its lower end 70 with means adapted upon rotation of the element, to scoop up liquid and throw it upwardly on to the inner face of the perforate cylinder, and means fitted above the first mentioned means, comprising an arrangement of 75 truncated cones designed to insure a uniform distribution of the liquid to be sprayed through said perforate cylinder by centrifugal action.

5. A rotative spraying element including a 80 perforate cylinder provided at its lower end with means adapted upon rotation of the element to scoop up liquid and throw it outwardly on to the inner face of the perforate cylinder, and annular guide means fitted 85 above the scooping means and designed to insure a uniform distribution of the liquid to be sprayed through said perforate cylinder by centrifugal action.

WALTER FRENCH SLATER.
